UNITED STATES PATENT OFFICE.

WILLARD B. CLEMENTS, OF WEST UNION, IOWA.

FLYING-MACHINE.

1,145,400.

Specification of Letters Patent. Patented July 6, 1915.

Application filed November 11, 1911. Serial No. 659,808.

To all whom it may concern:

Be it known that I, WILLARD B. CLEMENTS, citizen of the United States, residing at West Union, in the county of Fayette and State of Iowa, have invented certain new and useful Improvements in Flying-Machines, of which the following is a specification.

This invention relates to a steadyng oar for flying machines.

The main object of the invention is to provide a flying machine embodying among other characteristics means to balance and to prevent rolling of the machine with an auxiliary means for retarding and preventing swinging movement and sudden tipping of the machine.

Another object is to provide a steadyng oar for aeroplanes or any other type of flying machine which is adapted to overcome and prevent undue rolling and sudden tipping of the machine.

A still further object is to provide a steadyng oar adapted for connection with any type of flying machine and among other characteristics being foldable whereby it may be spread for action or folded, when desired.

With the above and other objects in view, the invention consists in the construction and novel combination of parts hereinafter more fully described, illustrated in the accompanying drawings, and pointed out in the claims hereto appended; it being understood that various changes in the form, proportion, size and minor details of construction, may be resorted to without departing from the spirit or sacrificing any of the advantages of the invention.

In the drawings:—Figure 1 is a front view. Fig. 2 is a perspective view looking toward the bottom of the machine. Fig. 3 is a side elevation. Fig. 4 is a bottom plan view.

It will be understood at the outset that my improved steadyng oar is not limited to use in connection with the flying machine illustrated in the accompanying drawings. The improved steadyng oar is readily applicable to flying machines of all types. However, I will proceed to describe the flying machine illustrated in the accompanying

drawings in which the reference character 1 indicates a rectangular-shaped frame composed preferably of tubular members braced by a plurality of tubular braces 2, which are crossed by another tubular brace 3. Wire cables 4 cross each other and are secured to opposite sides of the frame 1, as clearly shown. The connections between the braces 2 and 3 with the frame 1 are preferably reinforced. To the frame is secured the main plane *a* to effect proper lifting of the machine. Secured to the side bars of the frame 1 are wings 5 and 6 which are preferably curved transversely and which are braced at the ends of the frame by means of suitable braces 7 and 8. These wings 5 and 6 extend upwardly preferably throughout the length of the frame 1 to aid in lifting and to prevent undue rolling or tilting of the machine.

Secured to the frame 1 is a supplemental frame which consists of side bars 9 and 9', connected at their lower ends by a bar 10 having reinforced connection with said side bars.

Suspended from the frame 1 of the plane *a* by means of suitable braces 11 is a car 12, which may be of any form, preferably pointed at one or both ends. In any event, the bottom of the car at the forward end is preferably inclined upwardly, as at 13, with the forward end of the car provided with a window 14 through which the pilot may look in operating the machine. The car may be further supported by means of suitable braces 11'.

Tubular braces 15 and 16 connect the main frame 1 and the second mentioned frame and have bearings adapted to support the outer ends of the propeller shafts 17 and 18, respectively. The inner ends of the propeller shafts are journaled preferably in a support 19' carried by the car 12. On these propeller shafts are mounted propellers 19 and 20, of any suitable character. The propellers preferably operate on opposite sides of the window 14 of the car so as not to interfere with the view of the operator. The shafts 17 and 18 have beveled or other gear connections 21 and 22 with the beveled or other gears 23 and 24 carried by the shaft 25 of the engine 26 supported on the car preferably in the rear of the pilot house,

so that upon operation of the engine, the propellers are operated to throw wind against the main plane α .

Swingingly mounted upon the said bars 5 9 and 9' are rudders 27 and 28, respectively, which are connected together by any suitable flexible connection 29 and which also have cables 30 and 31, respectively, leading over a sheave 32 back to the pilot house of 10 the car for manipulation, as will be understood.

Extending forwardly from the frame 1 is a pair of braces 33 and extending forwardly from the bar 10 of the second frame, is a 15 pair of braces 34. These pairs of braces are connected together at their upper ends and are adapted to receive the horizontal pintle 35 of the rudder 36. This rudder 36 is controlled from the pilot house, preferably by 20 means of a cable 37 leading from one edge of the rudder over a sheave 38 and back to the pilot house, and also by a cable 39, which leads from the opposite side of the rudder, over a pulley 40, back to the pilot 25 house.

Mounted upon the part 10 of the second mentioned frame, are ground engaging wheels 41 adapted to coöperate with the ground engaging wheels 42; carried on the 30 axle 43 secured to the car 12 to permit the machine to be transported over ground, and also to provide means for moving the machine in the starting operation. The machine is first started by setting the engine 35 26 in operation. This causes the shaft 44 to rotate and by virtue of the beveled gear connection 45 of the shaft 44 with the beveled gear 46 on the rear axle 43, the machine is driven by the engine over the ground on 40 the wheels 41 and 42 until the operation of the propellers 19 and 20 creates such wind power as to act upon the main plane to lift the machine into the air.

It will thus be seen that I provide connections between the engine and the propellers and the drive shaft whereby power of the engine is converted in a horizontal direction to the rear wheels to start the machine and also the propeller. These connections between the wheels and the engine and between the engine and the propellers are so arranged that power of the engine may be converted directly either to the wheels which support the machine or to the propeller. It will also be seen that the wings 5 and 6 are so arranged as to overcome undue rolling and side tilting of the machine.

To reinforce or further provide against swinging movements and sudden tipping of the machine, I provide my steadyng oar and locate it at the rear of the machine. This steadyng oar consists preferably of a fixed rod 47 secured in any suitable manner at its inner end in the bracket 48. Swing-

ingly connected to this bracket 48 are either 48 rods 49 and 50. Connected over these rods 47, 49 and 50, is a sheet of canvas, silk or other suitable material 51, and when the operator desires to come down to the ground and when the machine is on the ground, the rods 49 and 50 may be swung on their pivots in the bracket 48 up against the rod 47 and in this way close or fold up the oar so that it will be out of the way and permit the machine to be disposed on the ground without danger of breaking or injuring the oar. 75

When the steadyng oar is in operative position, as shown in Fig. 4, and it is desired to close or fold up the same, it is only necessary for the operator to pull on the cord 52. The outer end of this cord 52 is fixedly connected at 53 to the rod 50 and passes over pulleys 54 and 55 on the rods 49 and 47, respectively. When the steadyng oar is folded, it may be unfolded by the operator who may pull upon the cord 53 which is fixedly connected to the rod 50 and which leads to the pilot house, as does the cord 52. Thus, the oar may be readily spread or folded and the rods on which the canvas, silk or other material is secured may be bamboo or any other suitable light material.

If desired, suitable flexible guy ropes 57, 58 and 59 may be secured to the lower part 55 of the steadyng oar with their opposite ends connected to the outer edges of the wings 5 and 6 of the machine. These guy ropes are preferably fastened back far enough on the wings to become taut when the steadyng oar is spread out to its fullest extent.

What is claimed is:—

1. The combination with a flying machine including a rigid frame, and a car rigidly secured thereto; of a relatively large collapsible steadyng oar secured to the car and projecting beneath the same and also projecting beyond the rear end of the frame work of the machine and held normally open when the machine is in the air and adapted the instant the machine begins to roll to prevent the car overturning incident to a rolling motion.

2. In a flying machine, a frame, a plane secured to the frame, a car suspended from the frame, a propeller journaled in the frame, a rudder operable on the frame, means for operating the rudder, and a relatively large collapsible steadyng oar mounted on the car and projecting beneath the latter and also projecting beyond the rear end of the frame and arranged centrally of the machine to co-act with the latter to retard lateral rolling motion of the machine.

3. The combination with a flying machine including a rigid frame and a car rigidly secured thereto; of a relatively large col-

lapsible steadyng oar secured to the rear end of the car and projecting beneath the same and also projecting beyond the rear end of the framework of the machine and 5 arranged in the line of the longitudinal axis of the machine and adapted to be maintained in open position during all the time the machine is in the air so as to act instantly upon rolling of the machine to pre-

vent overturning of the machine incident to a rolling motion.

In testimony whereof I affix my signature in presence of two witnesses.

WILLARD B. CLEMENTS.
